UNITED STATES PATENT OFFICE.

THOMAS J. LITTLE, JR., OF WOODBURY, NEW JERSEY, ASSIGNOR TO WELSBACH LIGHT COMPANY, OF GLOUCESTER, NEW JERSEY, A CORPORATION OF NEW JERSEY.

DESIGN FOR A METAL-NECKED GLOBE OR SHADE.

41,177.

Specification for Design.

Patented Feb. 14, 1911.

Application filed August 15, 1908. Serial No. 448,753. Term of patent 14 years.

To all whom it may concern:

Be it known that I, THOMAS J. LITTLE, Jr., a citizen of the United States, of Woodbury, Gloucester county, New Jersey, have invented a new, original, and ornamental Design for Metal-Necked Globes or Shades, of which the following is a specification, reference being had to the accompanying drawing, forming part hereof.

This invention relates to an article of manufacture, consisting of a neckless glass globe combined with a metal neck extending

within the glass body, the glass of the globe body being thicker than the metal of the neck.

The figure is a perspective view of a globe or shade, showing my new design.

I claim:

An ornamental design for a metal necked globe or shade, as shown and described.

THOMAS J. LITTLE, JR.
